ASSIGNORS OF NINE-TENTHS TO FREDERIC I. JOHNSON, OF FITCHBURG,
MASSACHUSETTS.

MACHINE FOR MAKING STEEL-WOOL.

1,300,002.

Specification of Letters Patent.

Patented Apr. 8, 1919.

Application filed March 17, 1917. Serial No. 155,628.

To all whom it may concern:

Be it known that we, FRANCIS A. PATON, a citizen of the United States, and HENRY L. KOENIG, a subject of the Emperor of Germany, both residing at Fitchburg, in the county of Worcester and Commonwealth of Massachusetts, have invented a new and useful Improvement in Machines for Making Steel-Wool, of which the following, together with the accompanying drawings, is a specification.

The present invention relates to a machine designed for the production of steel wool, and has particular reference to mechanism of this class which contemplates the successive removal of shavings from the surface of a steel wire, said shavings being of suitable fineness to constitute, when bunched together, in a mass, the product known as steel wool, which is employed in a variety of uses as a cleaning and abrasive agent.

The invention resides in the provision of mechanism adapted to produce said steel shavings at a rapid rate, by acting upon the entire outside diameter of the wire material, and so arranged as to effect successive reductions in the diameter of said wire, each reduction being productive of a quantity of shavings of the desired fineness. The invention contemplates the final reduction of the wire material to such a small size that no more shavings can be removed therefrom, the wire, when thus reduced in size still retaining its round cross section and being itself a salable product of the machine.

The foregoing and other objects of our invention are attained by the mechanism constructed and operated as set forth in the following description, reference being had in this connection to the accompanying drawings, in which

Figure 1 is a side view of our machine, the parts being shown assembled and in operation.

Fig. 2 is a view showing certain of the parts in end elevation.

Figs. 3, 4, and 5 are views illustrating various sizes and forms of cutting and shaping devices employed in our mechanism for the production of steel shavings.

Similar reference characters refer to similar parts in the different figures.

The machine of our invention, as shown in Fig. 1, includes a plurality of wire reducing, cutting and shaping devices, herein shown as three in number, which are mounted upon a stand or support 1, each device being held in a bracket 2 attached to the support 1. The brackets 2 afford slots or recesses for the reception of holders 3, which are detachably held in said slots by set screws 4, or the like. Each holder 3 has a circular recess in one of its faces, said recesses communicating with apertures 5 opening on the other face of each holder for the free passage of the material or wire therethrough. The recess in each holder 3 is provided for the reception of a flat circular cutting or shaping device, of the form shown, for example, by the devices 6, 7, and 8 of Figs. 3, 4 and 5, respectively, such a device filling and fitting snugly within said recess, and detachably held therein by means of a set screw 9, which may engage a depression 10 on the periphery of the device to hold the same firmly and rigidly in position.

At each end of the support 1, beyond the alined cutting and shaping devices above described, is preferably provided a guiding sheave 11 for the wire in its passage to or from said cutting and shaping devices. As shown in Fig. 1, the wire 12 is assumed to be traveling in the direction of the arrow A, said wire being drawn from a supply reel 13 at the left hand side of Fig. 1 and passing between a pair of cylinders 14, 14, whose surfaces are corrugated longitudinally to obtain a bite on the wire. The reel 13 is driven through a pulley and belt connection 15 from a second reel 16, the latter having rotation imparted thereto in either direction, as desired, from a belt 17, connected to a source of power, not shown. The means employed for reversing the direction of belt 17, to reverse, when desired, the rotation of reels 13 and 16, forms no part of our invention, and hence a description of the same is unnecessary, said reversing means being preferably connected to the source of power, not shown, which operates the belt 17. Adjacent the reel 16 on which the wire from reel 13, traveling in the direction of arrow A, is wound, are disposed cylinders 14, 14, which are identical in construction and ar-

angement with those adjacent the reel 13, the surfaces of said cylinders having co-operating longitudinal corrugations to obtain a bite on the wire in its passage to the 5 reel 16.

The cylinders 14, 14, of each pair are adapted to be rotated in unison through intermeshing spur gears 18, 18, the teeth of said gears being somewhat elongated and 10 preferably meshing loosely, so as to permit of a slight relative movement of the cylinders toward and from each other as herein-after described, while still maintaining the driving connection therebetween. One cylinder 14 of each pair has its shaft 19 journaled in a fixed bearing 20 on the frame member 21, said shaft 19 having a bevel gear connection 22 in each case with a shaft 23 which has a belt and pulley drive 24 with 15 the shaft of the adjacent reel, namely, in one case reel 13 and in the other case reel 16. The shaft of the other cylinder 14 of each pair is journaled in a bearing 25 which is 20 slideable, transversely, in ways 26 of the framework, a spring 27 operating at all 25 times to draw said sliding bearing and its cylinder 14 toward the other cylinder 14 of each pair, thus causing the longitudinal corrugations of said cylinders to make contact 30 with a wire 12 passing therebetween, irrespective of the diameter of said wire.

In the operation of the mechanism, assuming that a supply of wire to be reduced is carried by the reel 13, such wire is threaded 35 through the cutters and shapers carried by the several holders 3, and passed between the two pairs of co-operating cylinders 14, and in this disposition it is ready to be wound up on the reel 16. For operation in 40 this direction, as indicated by the arrow A, Fig. 1, the left hand holder 3 in Fig. 1 carries in its recess a shaping device such as that shown by the numeral 6 in Fig. 3, there being an aperture 28 therethrough 45 with a series of small triangular or pointed teeth 29 formed in the circumference of said aperture, the diameter at the base of said teeth corresponding substantially to the diameter of the wire. The next holder 3 to 50 the right will contain a cutting device, such as that shown at 7 in Fig. 4, said device having a plain aperture 30 therethrough, corresponding in diameter substantially to the diameter at the apex of the teeth 29 in 55 Fig. 3. The third holder 3, if it is found desirable to make still another reduction in the wire in the same draft, will have a shaping device in its recess, such as that shown by the numeral 8, in Fig. 5, the latter having a toothed aperture 31 therethrough, with 60 the diameter at the base of the teeth corresponding substantially to the diameter of the plain aperture 30, Fig. 4.

It will be understood that the drawing of 65 the relatively soft steel wire through alter-

nately toothed and plain shaping and cutting apertures, as above described, will result in the production of shavings of sufficient fineness to constitute, when assembled, the desired product, steel wool, the movement of the wire being effected, not only by the draft of reel 16 but by the bite of the two pairs of cylinders 14 thereon, both pairs rotating in the proper direction to move the wire in the direction of arrow A, Fig. 1. In 70 the operation above described, the first shaping device 6, by the action of its teeth 29, removes a great number of fine shavings from the surface of the wire, the latter emerging from said device 6 with its surface having a number of raised portions formed by the scoring action of teeth 29. These raised portions are shaved off or removed by the passage of the wire through the aperture 30, of cutting device 7, the 75 shavings from this, as well as from the previous operation being collected, as they fall, in a suitable receptacle, not shown. If desired, the wire emerging from cutting device 7, with an unscored surface, may be wound 80 up on reel 16 without any further reduction, or the shaping device 8 may be used to produce the same result on the reduced wire as the device 6, and if practicable, other alternating shaping and cutting devices gradually decreasing in diameter toward the end 85 of the draft may be employed, it being clear that our invention is not limited in any way to the number of successive shaving operations which may take place in a single drawing 90 of the wire through the machine.

In any event, after all the wire from reel 13 has been wound up on reel 16, the cutting and shaping devices in the several holders 3 are removed, said holders being reversed to 105 make their apertures 5 face in the opposite direction and a new series of alternating shaping and cutting devices are inserted and held in the recesses of said holders by said screws 9. Such new series of wire reducing 110 devices are substantially as those shown in Figs. 3, 4 and 5, except that their alternating plain and toothed apertures are smaller in diameter. The wire on reel 16 is threaded therethrough and between the adjusting cylinders 14, to be wound up on the reel 13, the direction of belt 17 being reversed for this 115 operation. Successive reductions of the wire in this fashion, each with the production of shavings of requisite fineness, are carried out until the diameter of the wire is so much reduced, that no further reduction is practicable, and then the wire is removed from the reels and constitutes itself a salable product.

We claim,

1. In a machine of the class described, the combination with means for continuously moving a wire circular in cross section, of means for scoring the entire periphery of the wire by a plurality of cuts, and means 120

125

130

for shaving the scored portion to produce a wire in circular cross section of less diameter than the diameter of the original wire.

2. In a machine of the class described, an annular cutter having internal scoring teeth, an annular cutter having a plain scraping edge, and means for moving a wire, circular in cross section, longitudinally through said toothed cutter and subsequently through said plain cutter.

3. In a machine of the class described, a pair of reels for carrying the wire to be operated upon, means for rotating said reels to draw the wire from one reel to the other, two pairs of rotating corrugated rolls engaging the wire between said reels, and a series of annular cutters interposed between said corrugated rolls.

4. In a machine of the class described, a series of detachable cutter holders having circular recesses, annular cutters held in said recesses, and means for moving a wire circular in its cross section longitudinally through said cutters.

5. In a machine of the class described, a cutter for scoring the outer surface of a wire, a cutter for scraping the wire, and means for moving a wire longitudinally past said cutters, comprising a pair of corrugated rolls, means for pressing the rolls against the wire, and means for rotating said rolls.
